G. W. Bradley.

GERSHOM W. BRADLEY, OF WESTON, CONNECTICUT.

Letters Patent No. 88,441, dated March 30, 1869.

IMPROVED SPIKE FOR OVER-SHOES.

The Schedule referred to in these Letters Patent and making part of the same.

To all whom it may concern:

Be it known that I, GERSHOM W. BRADLEY, of the town of Weston, county of Fairfield, and State of Connecticut, have invented a new and useful Improvement in the Mode of Constructing Spiked-Sole Over-Shoes, for walking on ice, and other purposes; and I do hereby declare that the following is a full and correct description thereof, reference being had to the accompanying drawing, and to the letters of reference marked thereon.

The nature of my invention consists in the manufacture of a spike, with a very thin and broad head, and the mode of attaching the same to the sole of the shoe.

To enable others skilled in the art to make and use my invention, I will proceed to describe the same.

In the drawing—

Figure 1 is a face view of the sole of an over-shoe, with the steel spikes attached.

Figure 2, a section of the sole, showing the mode of attaching the spikes.

The object of my invention is to make an over-shoe, for walking on the ice and other slippery places without slipping, and to have the spikes strong and light.

I construct the spikes B out of steel, struck into form by machinery, with the head made very thin, and flat, and broad, as shown in the drawing, the spike-part being tapered to a point, and made of any required length and size, and properly tempered.

I then make holes in the outer sole, A, to receive the spikes in home to the head.

I then place the inner and outer sole together, so that the flat head of the spike is between. (See fig. 2.) I then stitch or peg the two soles together in the usual manner, and also stitch or peg round the outer circle of the flat head of the spike, as at fig. 1, A; then the sole is finished to the upper in the usual manner.

By this mode of making and fastening the spikes to the sole, I gain a strong, light, and firm arrangement. The spikes may be made of any desired length, and any given number, more or less, can be used.

This over-shoe is convenient, economical, and a very useful article for walking in slippery weather, and for other purposes; is easily put on and fastened, and taken off.

I do not claim as new the spikes for shoes, but the form of the spike, and the manner of attaching to the sole.

What I claim as my invention, and desire to secure by Letters Patent, is—

The form of the spike for the purpose, and the mode of attaching the same to the sole, substantially as and for the purpose herein set forth.
